CLAIM

The ornamental design for a combined bottle and measuring cup cover, as shown and described.

DESCRIPTION

FIG. 1 is a side elevational view of a combined bottle and measuring cup cover showing my new design, the opposite side being a mirror image thereof;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view of the bottle shown without the measuring cup cover for clarity of illustration;

FIG. 7 is a rear elevational view of FIG. 6; and

FIG. 8 is a top plan view of FIG. 6.

FIG. 1**FIG. 2****FIG. 4**FIG. 3

FIG. 6

FIG. 5

FIG. 7***FIG. 8***
